VENTILATED METAL UMBRELLA

Doyle H. Simpson, Albuquerque, N. Mex.

Application March 29, 1948, Serial No. 17,725

3 Claims. (Cl. 108—3)

1

This invention relates to ventilated metal umbrellas of the type suitable for yard or beach use.

One of the objects of my invention is to provide a durable metal umbrella which can be easily assembled and erected in loose earth or sand and will provide a convenient sun shade.

Another object is to provide a metal umbrella top with means for ventilation so that heated air will travel in channels upward along the under-side of the top and out thru a central covered vent;

Still another object is to provide a metal umbrella having a top fabricated from sheet metal with novel and efficient mounting means on a supporting staff so that it can easily be attached to and detached from the staff; said attaching means being combined with an angle adjusting means arranged so that the top may be tilted relative to the staff to afford better shade protection during the early and late hours of the day, and so that the top may be rotated about portions of the staff to secure shade as desired.

Other objects will appear hereinafter.

I attain the foregoing objects by means of the construction and devices shown in the accompany drawings in which—

Figure 1 is a side elevation of my umbrella; Figure 2, a vertical section thereof drawn on a somewhat larger scale;

Figure 3, a partial plan view of the top;

Figure 4, an arcuate section of a portion of said top taken substantially on line 4—4, Figure 3;

Figure 5, a vertical section taken at right angles to the section shown in Figure 2; and

Figure 6, an elevational view of the central sleeve portion of the staff showing the side opposite to that appearing in Figure 1, but drawn on an enlarged scale.

Similar numerals refer to similar parts in the several views.

The umbrella, in general, consists of a top 2, a staff 3, a supporting point 4, and adjusting and mounting mechanism indicated by numeral 5.

The top is preferably made from light sheet metal first cut in the form of sectors and then folded on radial lines to provide alternate ridge sectors 10 and valley sectors 11. The material at the edges 12 of the ridge sectors is bent downward and slightly inward forming ridge side walls 14. At the bottom of these walls the material is bent outward at 16 to form the flat faces 15 of the valley sectors. Midway between the bends at the top edges 12 and the bends 16 the 55

2

side walls are perforated to provide a number of ventilating holes 18.

Where sectors forming the roof structure are joined a lap joint is formed, as at 19, Figure 4, between an upturned side wall flange 20 and a depending side wall flange 21. These lapped wall portions may be spot welded, or secured by metal screws, as desired. When all sectors are joined the top has a circular plan aspect, and a substantially conical elevation. The inner edges of the sectors, however, do not mutually meet to form an apex, but are cut so that a circular vent hole 23 is formed.

The perimeter of the top is scalloped to attain a pleasing appearance by cutting arcuate curves 25 and 26 at the ends of the ridge and valley sectors, respectively, and then bending the higher curved end portions 25 of the ridge sector ends downward at an angle to form tabs 27 so their outer edges lie in approximately the same plane as that of the arcuate ends 26 of the valley sectors. These tab ends 27 serve to close the outer ends of the ridge sectors.

Vent hole 23 is covered by a conical cap 29, directly beneath this is an inverted conical rest 30 with its perimeter 31 contacting the under side of the flat channel faces 15. These two conical elements are secured together by a long bolt 33 extending thru their apices. This serves to clamp 30 the central portions of the top sectors together and the lower apex portion 34 of the lower cone forms an adequate pivotal support for the entire top. A strengthening ring 30a may be attached to the lower face of top 2 when desired.

The staff 3 is composed of an upper nipple 36 threaded at each end, a sleeve 37 screwed onto its top end, a sleeve 38 threaded onto its lower end, a length of tubing 40 threaded into the lower end, and rotatably supported in a socket tube 41, at its lower end.

Top mounting and operating mechanism 5 includes the following: The upper sleeve 37, into which the lower pointed portion 34 of inverted cone support 30 is inserted, forms a pivotal socket 45 allowing the top to tilt relative to the axis of the nipple. Hold down and pivot bar 44, extends thru diametrically positioned holes 45 in the lower sleeve 38. One upwardly extending arm 46 of this bar hooks onto clevis 47 attached to 50 one of the side walls of a top ridge sector on the under face of the top. The opposite upwardly extending arm 48 hooks onto a clevis 50 similarly supported on the top and diametrically opposite to clevis 47.

The length of these bar arms is such that,

when upper sleeve 37 is screwed a short distance outward on nipple 36, its upper end supporting the point of cone rest 30 is forced upward and axially away from the attachment of bar 44 in sleeve 38. This draws clevises 47 and 50 tight on the outer ends of arms 46 and 48 and firmly supports the top on these arms so that it cannot tilt in the plane of these arms.

A handle 52 extends radially from sleeve 37 to give the user adequate leverage to turn the sleeve on nipple 36.

To tilt the top in a plane at right angles to that of said bar arms 46 and 48 I attach one end of a cable 54 to a link 55 secured to the under face of the top 2, draw it downward and inward thru a slot 56 in sleeve 38, wind it around that portion 57 of crank shaft 58 which is within sleeve 38 a few turns, and then run it out thru slot 59 upward and outward to a link 60 on the under face of top 2, positioned diametrically opposite link 55. When crank 61 is turned shaft 58 rotates and draws in one span of cable 54 while paying out the other. The direction of rotation of the shaft governs which span—either right or left, Figure 2—is drawn in and which span is payed out. Manipulation of the crank therefore tilts the top, the socket formed by the open upper end of sleeve 37 forming a fulcrum while the hooks in the upper ends of the bar 44 act as bearings in their respective clevises. The tilting movement of the top 2 is shown by dotted outline 62, in Figure 1.

A detent latch 64, Figure 6, is used to hold the crank shaft 58 in any desired rotative position and thus maintain the top at any desired angle of tilt.

In use, the point 41 is set in the earth and tube 40 inserted therein. The top is attached to the top of staff 3 as above indicated and then tilted, as desired, while the staff 3 is rotated to secure shade as desired.

Since it is obvious that many modifications can be made to the specific structure described, it is intended that the following claims be afforded a liberal construction.

I claim:

1. A ventilated metal umbrella having a conical top provided with a plurality of radial sector-shaped ridges with their sides perforated to secure ventilation, a hole at the apex thereof, a cover plate therefor, an inverted conical support positioned on the underside therebelow fixed to said cover plate, a staff having a tubular sleeve threaded onto its top end and receiving the pointed bottom of said supporting cone, a hold down bar having V-shaped arms extending from said staff upward to and attached to diametrically opposite positions on the under side of said top; tilting mechanism for said top including a cable having its ends secured to the underside of said top in diametrically opposite positions in right angular relation to the positions of attachment of said hold down bar arms and extending inwardly toward said staff to and wound around a rotatable crank shaft journaled on said staff, and a supporting point, having a socket to receive the lower end of said staff in rotatable relation therewith.

2. In a ventilated metal umbrella having a

conical top with radially extending sector shaped ridges having perforated side portions and a central opening, covered by a conical cap, a conical support on the underside of said top secured in axially alined relation to said cap, in combination with a supporting staff having a pointed socket, a tubular shaft rotatably secured therein, an intermediate sleeve on the upper end of said shaft a nipple secured in the upper end thereof, and a top sleeve threaded on the upper end thereof having a radial turning handle, and an open upper end constituting a socket receiving and supporting the lower pointed portion of said conical top support, a hold down bar extending thru said intermediate sleeve with its end portions extending angularly outward and upward from each side thereof and hooked into clevises on the under side of said top, a crank shaft extending thru and journaled in said intermediate sleeve in alined relation to said bar, having a latch to detain it in a plurality of rotative positions, and a cable for tilting said top on said staff upper nipple including a cable wound around said crank shaft at its middle, with its end portions extending upward and outward at right angles to said bar, and attached to the under side of said top; said top sleeve being adapted to screw upward against said conical support and draw said top tightly on said hold down bar end portions.

3. A ventilated metal umbrella comprising a top having a generally circular outline, a conical elevation, composed of alternate sector shaped ridge portions and channel portions connected by side walls depending from the edges of said ridge portions and downwardly converging having ventilating holes formed at intervals along their length, a ventilating hole formed in the center of said top, a conical cap piece covering said hole and an inverted supporting cone positioned on the bottom face of said top alined with said cap piece, a bolt drawing said conical pieces together in clamping relation on the top and bottom faces of said top; means for supporting said top comprising a tubular staff, a top sleeve screwed onto the upper end thereof having an open upper end to receive the lower pointed portion of said supporting cone, an intermediate sleeve incorporated in said staff, below said top sleeve; a top hold down bar extending diametrically thru said intermediate sleeve and angularly upward toward and secured to the underside of said top in diametrically opposite positions in jointed relation therewith; and a cable to tilt said top secured, at its ends, to the under side of said top at diametrically opposite positions in right angular relation to the positions of attachment of said hold down bar, extending inward to and wound around a crank shaft journaled in said sleeve with its axis paralleling said hold down bar, a crank on said shaft for rotating it, and a latch for detaining it in desired rotative positions; said top sleeve being adapted to tighten said top on said staff when screwed outward on said staff by forcing said top axially upward against the retention of said hold down bar.
